(57) **CLAIM**

The ornamental design for an aircraft fuselage closeout, as shown and described.

DESCRIPTION

FIG. 1 is a rear, top perspective view of an aircraft fuselage closeout showing our new design and its environment.

FIG. 2 is a detail rear, top perspective view thereof;

FIG. 3 is a top view thereof;

FIG. 4 is a right side view thereof; and,

FIG. 5 is a left side view thereof.

The portions of the drawing shown in a dash-dot-dash line connecting the ends of full lines define a boundary of claimed subject matter.
